United States Patent Office.

A. C. WURZBACH, OF MEMPHIS, TENNESSEE, AND WILLIAM WURZBACH,
OF NEW YORK, N. Y.

Letters Patent No. 66,273, dated July 2, 1867; antedated June 22, 1867.

IMPROVEMENT IN SPRING-CLASPS.

The Schedule referred to in these Letters Patent and making part of the same.

TO ALL WHOM IT MAY CONCERN:

Be it known that we, A. C. WURZBACH, of Memphis, Tennessee, and WILLIAM WURZBACH, of New York, county of New York, and State of New York, have invented a new and improved "Clasp;" and we do hereby declare that the following is a full and exact description thereof, reference being had to the accompanying drawings, and to the letters of reference marked thereon, of which—

Figure I is a top view of the clasp when adjusted.

Figure II is a view with the tongue adjusted at the fourth slot.

Figure III is the adjustable tongue.

Figure IV is an end view of the clasp.

The nature of our invention consists in providing a neat and durable clasp that can be adjusted to suit the amount that is required to be carried in the pocket-book without the use of any elastic substance whatever.

Construction.

The clasp is composed of three pieces: the cap *a*, the plate *b*, and the tongue *e*. The plate *b* is a thin, flat piece of metal, cut out the desired shape to receive the cap *a*. The cap *a* is made of steel, or any other flexible material that has the proper substance. It is cut out to the required form, and slitted so as to form the spring *c*, and then attached to the plate *b*, as shown at Figs. I and II. The tongue *e* is then made of any suitable material with slots or indentures *n* *n'* *n''* *n'''* *n''''* to receive the catch *i* on the spring *c*. The clasp, after being made, is attached to the pocket-book belt, elastic, or to any wearing apparel where it may be applied and made fast.

Operation.

The clasp is now made and adjusted to the pocket-book belt or elastic, and is locked by slipping the tongue *e* into the elongated hole between the cap *a* and the plate *b*, and is held to its place by the means of catch *i* on the spring *c* inserting itself into one of the slots *n* *n'*, &c., in the tongue *e*, according to the quantity contained in the book. The book is opened by lifting the spring *c* so as to disengage the catch *i* from the slots *n* *n'*, &c., in tongue *e*.

Advantages.

The advantage of our invention consists in furnishing a neat, durable, and simple adjustable clasp without the use of any expansive material, that can be applied to a pocket-book or any wearing apparel with facility.

Claim.

What we claim as our invention, and desire to secure by Letters Patent, is—

An adjustable clasp, when constructed and operated substantially as herein described.
